ANCHOR

Application filed June 25, 1930. Serial No. 463,793.

This invention relates to devices adapted to be imbedded in the earth for anchorage purposes and is particularly directed to an anchor adaptable for use in firmly securing or anchoring guy wires to the ground.

The chief difficulty encountered in the application of anchoring devices for guy wires or the like is that the anchor after the passage of time tends to loosen within the ground and the guy wire thereupon becomes slack. Various devices have been developed for causing the anchor to positively and definitely remain in the original position without shifting due to the constant heavy pull or strains on the guy wire tending to extract the anchor from the ground.

It is therefore an object of this invention to provide an improved anchor or ground plate for guy wires or the like which has an extremely effective contour rendering the anchor incapable of dislocation due to strains on the guy wire. This objective is primarily accomplished by the particular contour of the upper surface of the anchor which disposes an upper concave surface in engagement with the earth above it in such manner that it would be necessary to break loose or displace all the ground above the anchor before the anchor will be dislocated.

It is another object of the present invention to provide a new method of inserting or planting an anchor in firmly anchored position without disturbing the major portion of the ground above it. For this purpose a hole is drilled into the earth obliquely relative to the surface thereof and undermining or extending under the spot at which the guy wire is to be anchored, and an anchor post or rod is driven downwardly from the point of guy wire attachment entering the hole at right angles or transversely thereto, whereupon the anchor is lowered into position upon the lower end of the rod and against the lower side of the hole. The hole is then refilled and the dirt is tamped into position over the anchor.

In view of the foregoing, it is another object of this invention to provide a new and improved anchor of arcuate cross sectional contour constructed on a radius correspond-

ing to the radius of the hole, which anchor is adapted to lie against the lower side of the hole to permit the replacement of the earth over the anchor thus placed. The anchor is located in this manner so as to permit a complete refilling of the upper side of the cavity at the point of entry of the rod for the reason that this side of the aperture is generally caved in by the entrance of the driven rod.

It is another object of this invention to provide a novel device for permitting ready insertion of the rod and for effecting a speedy and convenient couple between the anchor and the rod within the ground which couple is incapable of loosening after the earth has been replaced and the guy wire stretched.

It is still another object of this invention to provide a guy wire anchorage means wherein the anchor plate disposed within the ground and the guy wire connecting rod are flexibly coupled at a point outward or forward of the general plate surface for delivering the pulling strain exerted through the rod to a coupling point in an advanced position relative to the plate, and to further provide that the central shape of the plate at the point of coupling is such that the tensional stresses on the plate are extended toward the margins thereof rather than to the center. By this arrangement, it is provided that there is less opportunity for collapsing of the central portion of the plate and due to the particular transverse curvature of the plate in combination with this coupling means an unusual sturdy anchor plate is provided.

Other objects and certain advantages will be more fully apparent from a description of the accompanying drawings, in which:

Figure 1 is a general view illustrating a cross section of the earth adjacent a pole and showing a guy wire anchored by the device and by means of the method of the present invention.

Figure 2 is a top plan view of the anchor.

Figure 3 is a sectional view taken on line 3-3, Figure 2, illustrating the anchor in longitudinal section and showing the anchor rod in position.

Figure 4 is a sectional view taken on line 4-4, Figure 3, illustrating the semicircular

contour of the anchor adaptable for fitting the circular curvature of the hole.

Figure 5 is a perspective view illustrating the spear head for the rod removed therefrom.

Generally described, the elements of the present invention are the anchor rod 10 and the anchor or ground plate 11. These elements are inserted or placed within the earth 10 separately and are coupled in set position. The environment necessary is an element to be braced such as a post 12, a guy wire 13 extending down from the post and a cavity 14 drilled into the earth by means of an auger 15 obliquely to the earth surface and toward the post.

Referring specifically to the drawings, the details of the mentioned elements are as follows. The anchor 11 consists of a formed plate which is generally straight in longitudinal section and arcuate in cross section. An irregular pyramid or hollow cone 15 is formed upwardly intermediately of the length of the plate. This cone or pyramid is 25 slightly flattened in cross section so as to permit greater exposed concave area on the upper surface of the plate. The anchor may be of relatively light plate material provided its strength is sufficient to prevent deformation.

The central raised portion or irregular pyramid includes a slot 16 in a portion of the wall thereof which may be described as the end portion or longitudinally disposed side 35 relative to the plate. The slot 16 extends substantially from the straight longitudinal extent of the plate to the apex of the cone. The slot is of a substantial width from the bottom of the pyramid a considerable distance upwardly. Toward the top of the pyramid the width of the slot is reduced as at 17. This slot permits the plate to be inserted over the headed end of the rod to which the guy wire is connected, the lower portion of the slot 40 being of a suitable width for permitting convenient entrance of the head to the interior of the hollow cone and the remainder of the slot being of a width suitable for permitting travel of the plate downwardly about the rod 50 against the head, whereby the head cannot be extracted axially through the apex of the cone or laterally displaced. Toward what may be termed the upper end of the plate, an aperture 18 is provided permitting attachment 55 of the anchor to the hook of an inserting device of some sort for initially lowering the anchor into position within the cavity and manipulating the same into its position upon the head of the rod.

60 The rod 10 provides an eye 19 at one end and is screw-threaded on the opposite end. Upon initial insertion into the earth, the rod is free of attachment to the guy wire. For facilitating insertion of the rod into the earth, a spear head 20 is provided. This spear head

includes a sharp point and a rounded opposite or upwardly disposed end. A bore 21 is provided in the spear head extending axially thereof from the rounded end inwardly and stopping interiorly of the pointed tip.

70 A square cross passage 22 is provided intermediate of the length of the head transversely intersecting the aforesaid bore. This passage is of slightly greater width than the distance between opposing faces of the nut 23. The nut is slid into position from the side of the head and aligned with the central bore, being held against rotation by the engagement of its opposite sides with the sides of the passage and the rod is then easily screwed 80 into adjusted position in the nut.

85 With the spear head in position on the lower end of the rod, the rod is driven into the earth in alignment with the proposed taut extent of the guy wire and at right angles to the auger hole until the headed end of the rod breaks into the auger hole. The anchor is then slid along the lower side of the oblique hole, its curvature approximately fitting the curvature of the hole, the anchor being lowered by means of a hooked tool attached to the aperture at its upper end.

90 The anchor is slid over the head through the wide portion of the slot and the anchor rod then assumes a position in axial alignment with the cone of the anchor. Thereupon the rod is drawn upwardly until the rounded end of the head engages in the correspondingly rounded inner surface of the apex of the hollow cone. Thereupon the 95 auger hole is entirely filled with the previously removed earth and the earth is firmly tamped in position.

100 By placing the anchor against the lower side of the auger hole, it is possible to tamp the dirt back into place to fill up the cavity caused by entry of the spear head into the auger hole. It will be apparent that an extremely small auger hole is sufficient for placing the anchor. Therefore, there is a 105 considerable amount of undisturbed earth between the lowermost depth of the cavity and the surface of the earth at the point of attachment to the guy wire, which undisturbed earth is incapable of displacement by 110 normal strains on the guy wire.

115 For the anchor to become loosened or to be extracted from the earth, it is necessary that a block of earth, the cubical contents of which are determined by the width of the anchor 120 and the distance of the anchor to the surface of the earth, be bodily removed or torn up. The anchor, due to its peculiar curvature, is incapable of providing any wedging action 125 for easing extraction of the anchor. With the anchor thus placed, the guy wire is attached to the eye portion at the upper portion of the rod and suitably tightened by any means conventionally employed.

130 The inner end of the spear head being

rounded and engaging with the rounded inner side of the apex of the anchor plate, a rocking or flexible connection is provided. This connection within the apex is well in 5 advance of the general plate surface and the walls of the hollow cone extending outwardly toward the edge margin of the plate deliver the tension more uniformly throughout the plate.

10 Having described by invention, I claim:

1. In a device of the class described, an anchor plate having a concave upper surface and a hollow pyramid centrally thereof, said pyramid including a slot in the side wall 15 thereof of narrow width toward the apex, and a rod having a head on its lower end adapted to be inserted into the pyramid through the slot.

2. A device for anchoring guy wires consisting of a plate having a straight longitudinal extent and arcuate cross section and including a central portion extended from the concave side of the plate provided with means for attachment to the part to be anchored, the concave side being adjacent to 25 the guy wire.

3. An anchor, comprising, a plate, arcuate in cross section and generally straight longitudinally, a raised portion formed centrally 30 and at the concave side thereof, said raised portion having a lateral orifice formed therein, and means insertable into the apex of the raised portion through the orifice for attaching an element to be anchored thereto, 35 said element being on the concave side of the plate.

4. A method of anchoring guy wires consisting of drilling a hole obliquely into the earth and toward the object to be braced by 40 the guy wire, driving a rod into the earth in alignment with the guy wire to be attached thereto at right angles to the hole for extending the inner end of the rod into the hole, lowering a plate into the hole into engagement with the inner end of the rod against the lower side of the hole, and replacing the earth within the hole above the plate and against the upper surface of said plate.

5. In an anchoring device, a plate having a concave upper surface, a hollow irregular cone rising centrally of said plate and having a rounded inner surface at the apex thereof, a rod, said rod having a spear head adjustably mounted on one end, said spear head having a rounded inner end adapted to engage the rounded inner side of the apex of the hollow cone, and said cone laterally slotted to permit lateral insertion of the spear 55 head and rod within the cone.

6. In an anchoring device, a plate having its upper surface concave in cross section and generally straight in longitudinal section, including a hollow pyramid rising centrally 60 of the plate, a rod, a spear head for said rod,

said spear head having an axial bore extending into the rear end thereof, a transverse rectangular bore intersecting said axial bore, a nut insertable through said rectangular bore and held against rotation therein, said rod having screw threads on its inner end engaged through the nut, said spear head having a rounded inner end in engagement with the inner side of the apex of the hollow pyramid, and said pyramid laterally slotted 70 to permit lateral insertion of the spear head and rod into the pyramid.

In witness whereof I hereunto subscribe my name.
